ABSTRACT OF THE DISCLOSURE

In the NTSC color television system a burst of eight or more cycles of the color subcarrier frequency is included in the transmitted signal following each horizontal line synchronizing pulse. This burst is suppressed during vertical blanking intervals. Apparatus is provided for deriving burst "flag" pulses from differentiated horizontal synchronizing pulses and for inhibiting the burst flag pulses during vertical blanking intervals by deriving an inhibiting waveform from integrated vertical synchronizing pulses.

BACKGROUND OF THE INVENTION

This invention relates to apparatus for generating a burst flag pulse which is used for adding an intermittent reference subcarrier to a composite color television signal in the color encoder portion of a television transmission system.

In the NTSC system of color television transmission, a burst of eight or more cycles of a color subcarrier is transmitted on a pedestal portion of the composite television signal following each horizontal line synchronizing pulse. The subcarrier burst is used in a television receiver to synchronize an oscillator which operates at the color subcarrier frequency, the oscillator being arranged to produce a continuous reference subcarrier wave for demodulating color information contained in sidebands of a modulated suppressed subcarrier color signal. The standards for such color transmission are well known and are set forth in FCC Public Notice No. 53-1663 dated Dec. 17, 1953.

In the transmitting portion of the television system, a burst flag pulse is generated following each horizontal (line) synchronizing pulse but is omitted during the vertical blanking period. During a vertical blanking period, a serrated vertical synchronizing pulse and equalizing pulses, the serrations and equalizing pulses occurring at twice the horizontal line synchronizing pulse frequency, are generated. It is known in the art that the horizontal synchronizing pulses, the equalizing pulses and the vertical synchronizing pulse components may be applied to a gating network including multivibrator stages to generate the burst flag pulses and to inhibit the burst flag pulses during the vertical blanking period. However, the number of stages required to generate and inhibit the burst flag pulses in this manner requires complex and undesirably costly circuitry.

Accordingly, it is an object of this invention to provide improved apparatus for generating burst flag pulses from a train of pulses including horizontal synchronizing pulses, equalizing pulses and vertical synchronizing pulses.

In accordance with the present invention, improved apparatus is provided in a television system for deriving a burst flag pulse from a train of pulses including horizontal line synchronizing pulses, equalizing pulses and vertical synchronizing pulses. Separate means are provided for differentiating and for integrating the train of pulses described above. The outputs of the differentiating and integrating means are combined and coupled to an amplitude detector which generates a burst flag pulse following each horizontal synchronizing pulse and which inhibits the burst flag pulse during the vertical blanking period.

2

The invention is more fully described in the following specification taken in conjunction with the accompanying drawings in which:

FIG. 1 is a schematic and block diagram of an embodiment of the invention;

FIG. 2 is a series of diagrams of related pulse waveforms produced at specified points in FIG. 1; and

FIG. 3 is a block diagram of a second embodiment of the invention.

DESCRIPTION OF THE INVENTION

In the circuit of FIG. 1, an input terminal 12 is adapted to be coupled to a synchronizing pulse train source 10, the pulse train including recurring horizontal line synchronizing pulses, equalizing pulses, and vertical synchronizing pulses. Such a pulse train is shown in waveform 70a of FIG. 2. A first capacitor 14 is coupled between input terminal 12 and the junction of first and second resistors 22 and 24. Resistors 22 and 24 are connected in series in the named order between negative (—) and positive (+) voltage sources.

A second capacitor 16 is coupled between input terminal 12 and the junction of third and fourth resistors 18 and 20. Resistors 18 and 20 are coupled in the named order between the positive and negative voltage sources mentioned above.

A resistor 26 is connected from the junction of resistors 22 and 24 to an input terminal 36 of an operational amplifier 40. A variable capacitor 34 is connected between terminal 36 and ground.

A resistor 28 is connected from the junction of resistors 18 and 20 to the cathode of a diode 32. The anode of diode 32 is connected to terminal 36 of amplifier 40. An integrating capacitor 30 is connected from the junction of resistor 28 and diode 32 to ground.

A biasing network comprising series-connected resistors 50, 44, and 48 is adapted to be connected between positive (+) and negative (—) voltage sources. A wiper arm 46 of variable resistor 44 is connected to a bias input terminal 38 of operational amplifier 40. A decoupling capacitor 42 is connected between terminal 38 and ground.

An output signal from the amplifier 40 is developed between an output terminal 52, and ground.

During operation of the burst flag generator shown in FIG. 1, the synchronizing pulse train shown in waveform 70a of FIG. 2, which comprises horizontal synchronizing pulses 71, equalizing pulses 72, and serrated vertical synchronizing pulses 73, is applied via terminal 12 to a differentiating network including capacitor 14 and resistors 22 and 24. The relative values of resistors 22 and 24 and the positive and negative supply voltages (+ and —) determine the DC voltage level at the junction of resistors 22 and 24. The DC voltage level is selected such that the output waveform produced at the junction of resistors 22 and 24 is always negative. The effect of the differentiating network 14, 22, 24 on the horizontal synchronizing pulses, the equalizing pulses, and the serrated vertical synchronizing pulses, respectively, may be seen in waveform 70b of FIG. 2 by referring to respective differentiated pulses 75, 76, and 77. The amplitudes of each of the three types of pulses 71, 72, 73 are equal while their durations differ. Capacitor 14 serves to pass the leading edge of the waveform (i.e., a high frequency change) but begins to charge to the peak voltage of the pulse immediately thereafter. The output voltage produced at the junction of resistors 22 and 24 therefore declines during the pulse interval (i.e., between the pulse leading and trailing edges). Since the horizontal synchronizing pulses are approximately twice the duration of the equalizing pulses, capacitor 14 is charged to a greater voltage level during the horizontal synchronizing pulses than during the equalizing pulses.

Therefore, at the termination (trailing edge) of the horizontal synchronizing pulses, the output waveform **70b** returns to a more positive (or, as the case may be, a less negative) voltage than in the case of the equalizing pulses (compare pulses **75** and **76**). In this manner the trailing edges of the horizontal synchronizing pulses are susceptible of amplitude separation from the trailing edges of the equalizing pulses. It should be noted that the vertical synchronizing pulse is broken up or serrated and includes relatively long duration components separated by short duration intervals. The long duration or wide components of the vertical synchronizing pulses are greater in duration than either the horizontal synchronizing pulses or the equalizing pulses. Therefore, the trailing edges of the wide vertical synchronizing pulse components will produce the highest positive peaks as shown by pulses **77** of waveform **70b** of FIG. 2. It will be shown subsequently how the peaks of pulses **77** are brought below the peaks of the other pulses so that the pulses **75** provide the most positive or, if desired, by changing the DC level, the least negative peak voltage.

The pulse waveform **70a** applied to terminal **12** is also coupled through coupling capacitor **16** and applied to the integrating network including resistor **28** and capacitor **30** (capacitor **16** is substantially larger in value than capacitor **14**). The relative values of resistors **18** and **20** and the magnitude of the supplied voltages determine the DC voltage level at the junction of resistors **18** and **20**. The time constant of the integrating network **28**, **30** is long relative to the time constant of the differentiating network **14**, **22**, **24** previously described. The width or duration of the vertical synchronizing pulse components **73** is greater than the width of either the horizontal synchronizing pulses or the equalizing pulses. Because of the relatively long time constant of the integrating network **28**, **30**, capacitor **30** will not be charged significantly by the narrow horizontal synchronizing pulses **71** and equalizing pulses **72**, but will be charged by the relatively wide vertical synchronizing pulse components **73** so as to assume a DC level during the vertical synchronizing pulse interval. Hence, the output of the integrating network **28**, **30**, appearing at the junction of resistor **28** and capacitor **30**, will be as shown by the waveform **70c** of FIG. 2. The width of portion **78** of waveform **70c** is substantially equal to the total vertical synchronizing pulse interval of pulse train **70a**. Resistors **18** and **20** are selected such that the DC voltage at their junction, and at the cathode of diode **32**, is slightly positive and the portion **78** of waveform **70c** is negative. As previously mentioned, the voltage level in the differentiating network path, and at the anode of diode **32**, is always negative, so diode **32** is reverse biased except during the portion **78** of waveform **70c**, that is, during the vertical synchronizing pulse interval.

Thus, diode **32** conducts in the presence of the integrated vertical synchronizing pulse and the waveform **70c** is combined at terminal **36** with the pulses (waveform **70b**) from the differentiating network **14**, **24**. The combined waveform appearing at the input terminal **36** of the amplifier **40** is shown in waveform **70d** of FIG. 2. The effect of the combination of the differentiated and the integrated pulses is to produce an output pulse from amplifier **40** (see waveform **70e**) following each horizontal synchronizing pulse but not during the vertical synchronizing or equalizing pulse intervals.

Resistor **26** and variable capacitor **34** partially integrate the differentiated pulses shown in waveform **70b**. The effect of such integration is to alter the rise time of the trailing edges of the differentiated horizontal synchronizing pulses. The altered trailing edges of these pulses are shown by the dotted lines **75a** in waveform **70d** of FIG. 2. Capacitor **34** is much smaller than capacitor **30**, so the effect of capacitor **34** on the integrated vertical synchronizing pulses is negligible.

Operational amplifier **40** serves as a level or amplitude

detector for the combined waveform **70d** appearing at its input terminal **36**. Amplifier **40** is arranged to provide a nominal 10 volt output pulse with an input of a nominal value of 10 millivolts. The amplifier **40** typically includes provision for an input bias voltage. For example, a commercially available RCA model CA 3015 integrated-circuit operational amplifier provides the desired operating characteristics. An adjustable bias voltage obtained from the wiper arm **46** of variable resistor **44** is applied to bias voltage input terminal **38** of amplifier **40**. The bias voltage is adjustable in the range of the peaks of the differentiated horizontal synchronizing pulses. Since it is desired to amplify only the peaks of the differentiated horizontal synchronizing pulses, the bias voltage appearing at bias terminal **38** is adjusted such that only the peaks of the differentiated horizontal synchronizing pulses exceed this level. The peaks of the differentiated equalizing pulses and vertical synchronizing pulse components fall below the bias voltage level and will not produce an output at terminal **52** of amplifier **40**. The peaks of the differentiated horizontal synchronizing pulses typically are arranged at a nominal one-half volt above the bias voltage level and are of sufficient amplitude to drive amplifier **40** into saturation. A rectangular output pulse therefore is produced at terminal **52** following the trailing edge of each horizontal synchronizing pulse. The width of the output pulse is dependent upon the shape of waveform **75a**.

The output of amplifier **40**, appearing at output terminal **52**, is a rectangular burst flag pulse **80**, shown in waveform **70** of FIG. 2, delayed from the trailing edge of the horizontal synchronizing pulse. The amount of delay of pulse **80** from the trailing edge of the horizontal synchronizing pulse may be varied by adjusting capacitor **34** which alters the slope of the trailing edge of the horizontal synchronizing pulses. The width of the rectangular burst flag pulse **80** may be adjusted by varying the bias voltage applied to amplifier **40**.

Another embodiment of the present invention is shown in FIG. 3. The arrangement in this embodiment produces a burst flag pulse which is delayed from the leading edge of the horizontal synchronizing pulses of the pulse train supplied by source **10**. A pulse train, shown in waveform **70a** of FIG. 2, is supplied by source **10** to input terminal **61** of delay multivibrator **60** and to input terminal **12** of circuit **11**. Circuit **11** represents the circuit shown in FIG. 1 with the exception that capacitor **34** is omitted. The operation of the circuit **11** is the same as described with reference to FIG. 1 except that there is no provision to vary the delay of the rectangular pulse appearing at terminal **52** of circuit **11**. A variable resistor **62** controls the pulse width of multivibrator **60**. An output terminal **63** of multivibrator **60** is connected to an input terminal **55** of a burst flag multivibrator **54**. The output terminal **52** of circuit **11** is connected to an inhibit terminal **57** of multivibrator **54**. A variable resistor **56** controls the width of the burst flag pulse appearing at output terminal **58**.

Adjustment of variable resistor **62** varies the delay of the trailing edge of pulses produced by multivibrator **60**. The trailing edge of such pulses trigger the burst flag multivibrator **54**. The output appearing at terminal **52** (see explanation of FIG. 1) inhibits multivibrator **54** except when a pulse is present at terminal **52**. An output pulse is produced at terminal **52** following each horizontal pulse, but no output pulse is produced during the equalizing or vertical synchronization pulse intervals. This is the same condition as described with reference to FIG. 1. Thus, multivibrator **54** is enabled only during intervals following the trailing edge of the horizontal synchronizing pulses. The trailing edge of the pulses produced by multivibrator **60** are applied to input **55** of multivibrator **54** at some time during the "enabled" period of multivibrator **54** (as determined by the adjustment of resistor **62**). A burst flag pulse therefore is generated by multivibrator **54** at output terminal **58**, the pulse being delayed

from the leading edge of the horizontal synchronizing pulse and being of a duration determined by variable resistor 56.

What is claimed is:

1. Apparatus for deriving pulses from a pulse train including recurring first, second, and third pulses, said second pulses being wider than said first pulses and said third pulses being wider than said second pulses, said apparatus comprising:

an input terminal adapted to be connected to a source of said pulse train,
a first output terminal,
means coupled to said input terminal for differentiating said first, second, and third pulses,
means coupled to said input terminal for integrating primarily said third pulses,
means coupled to said integrating means and to said differentiating means for combining the pulses derived therefrom, delaying means coupled in circuit between said input terminal and said first output terminal for effectively delaying at least one of said first, second, and third pulses, and
means coupled between said combining means and said first output terminal for detecting said differentiated second pulses and forming rectangular output pulses therefrom, said means also inhibiting said rectangular output pulses during the interval of said integrated third pulses.

2. Apparatus according to claim 1 wherein said means for detecting said differentiated second pulses includes an operational amplifier having input and output terminals for level-detecting said differentiated second pulses.

3. Apparatus according to claim 2 wherein said operational amplifier has a bias voltage input terminal adapted to be connected to a source of adjustable bias voltage, whereby an output pulse is derived from said operational amplifier only when said differentiated second pulses exceed the level of said bias voltage.

4. Apparatus according to claim 3 wherein said delaying means includes a capacitor connected between said combining means and a point of reference potential for altering the slope of the leading edges of said differentiated pulses whereby the delay between said second pulses and said rectangular pulses is determined.

5. Apparatus according to claim 3 wherein said delaying means includes a first multivibrator and said means for forming a rectangular pulse includes a second multivibrator, each of said multivibrators having input and output terminals,

said first multivibrator having its input terminal connected to said pulse train input terminal and its output terminal connected to an input terminal of said second multivibrator, and

said second multivibrator having its output terminal connected to said first output terminal.

6. Apparatus according to claim 5 wherein said second multivibrator has an inhibit input terminal connected to said output terminal of said operational amplifier, whereby there is an output obtained from said second multivibrator only when there is a pulse applied to said inhibit input terminal.

7. Apparatus according to claim 6 wherein each of said first and second multivibrators has an adjustable delay time, the delay time of said first multivibrator determining the delay between said second pulse and said rectangular output pulse, and

the delay time of said second multivibrator determining the duration of said rectangular output pulse.

8. Pulse generating means comprising:

means for providing a train of pulses including first, second and third pulse components, said second pulse components being of greater duration than said first pulse components, and said third pulse components being of greater duration than said second pulse components;

means coupled to said pulse train providing means for differentiating said pulse components,

means coupled to said pulse train providing means for integrating said pulse components, and

means coupled to said differentiating and integrating means responsive jointly to differentiated and integrated pulse components for producing output pulses in timed relation with respect to said second pulse component.

9. Pulse generating means according to claim 8 wherein said jointly responsive means inhibits said output pulses during the interval of said third pulses.

10. Pulse generating means according to claim 9 wherein said jointly responsive means includes means for timing said output pulses from the trailing edge of said second pulses.

11. Pulse generating means according to claim 9 wherein said jointly responsive means includes means for timing said output pulses from the leading edge of said second pulses.
